2 Claims. (Cl. 167—58)

The present invention relates to new esters of 1,3,5(10)-estratriene-3,16,17-triol, and novel pharmaceutical compositions with persistent efficacy which contain as its effective ingredients 1,3,5(10)-estratriene-3,16,17-triol esters. To be more specific, this invention relates to a new ester of 1,3,5(10)-estratriene-3(β),16(α),17(α)-triol and monobasic saturated fatty acid (2-6 carbon atoms) esters and benzoic acid esters of 1,3,5(10)-estratriene-3,16(α),17(β)-triol; and also relates to pharmaceutical compositions which contain as its effective ingredient 1,3,5(10)-estratriene-3(β),16(α),17(α)-triol ester and a monobasic saturated fatty acid (2-6 carbon atoms) esters, or benzoic acid esters, of 1,3,5(10)-estratriene-3,16(α),17(β)-triol; and are used for treatment of vaginitis, cervicitis, climacteric disturbance, menorrhagia, etc., and for shortening labour and facilitating delivery.

There are several known isomers of 1,3,5(10)-estratriene-3,16,17-triol, depending on the configuration of hydroxyl groups, among them, one, so-called estriol and clinically applied, is 1,3,5(10)-estratriene-3,16(α),17(β)-triol and is just like estradiol a kind of naturally occurring estrogen. However, according to the results of bioassay, its estrogenic activity is only about 1/100 comparing with that of estradiol; for this reason estriol has been regarded as a mere metabolite of estradiol and one having relatively small efficacy for treatment. Meanwhile, Puck et al. discovered in 1957 that estriol is remarkably inferior to estradiol in the effect of proliferating the endometrium, but superior to it in the effect on the endocervix and vaginal epithelium; and thereafter the merit of estriol as a means of treatment has been re-evaluated.

Estradiol by virtue of its inhibition of the production of gonadotropin in the pituitary gland is highly prized as a powerful means of controlling climacteric disturbance, but its strong function of proliferating the endometrium causes a withdrawal bleeding of the uterus, which has been regretted as the fatal side effect of estradiol.

By contrast, estriol, even if administered in large doses, will not exert such a strong effect of endometrium proliferation as to cause a uterine bleeding, so that it has been highly appreciated as a safe means of treating climacteric disturbance and menorrhagia; on account of its specific action it can be safely and effectively prescribed against vaginitis and cervicitis.

On the other hand it is well known that a significant increase of estriol is observable in the pregnant urine at the ultimate stage of pregnancy; Puck et al. attributed to this increase an effect of making the pelvis flexible; widening, softening and dilatating the cervix and vagina. Based on this specific action of estriol upon the cervix and vagina, application of estriol to delivery has come to be tried.

Meanwhile, 1,3,5(10)-estratriene-3(β),16(α),17(α)-triol is less strong in its estrogenic action than 1,3,5(10)-estratriene-3,16(α),17(β)-triol; therefore it has never been adopted for treatment. In the meantime, 1,3,5(10)-estratriene-3,16(α),17(β)-triol triacetate and 1,3,5(10)-estratriene-3,16(α),17(β)-triol 16,17 diacetate are known

2

as derivatives obtained when the above-mentioned estriol is detected or identified, but it has never been applied for clinical purposes.

Estriol, as stated above, has been clinically applied in different forms; injection for parenteral use, tablets for oral administration, or tablets for vaginal use. To secure full treatment effect, however, it must be repeatedly administered.

The present inventors have sought for many years for the method of making the effects of the above-mentioned estriols stronger and more persistent and finally discovered that through esterification of the hydroxyl groups of estriols by monobasic saturated fatty acids or benzoic acid, the estrogenic action of estriol could be rendered persistent and stronger.

Thus, the objective of the present invention is to offer new esters of 1,3,5(10)-estratriene-3,16(α),17(β)-triol and 1,3,5(10)-estratriene-3(β),16(α),17(α)-triol which can hold an efficacy for a long time by a single administration and to offer a pharmaceutical composition, usable for treatment of vaginitis, cervicitis, menorrhagia, etc., and for shortening labour and facilitating delivery, that contains as its effective ingredients esters of 1,3,5(10)-estratriene-3,16(α),17(β)-triol and an ester of 1,3,5(10)-estratriene-3(β),16(α),17(α)-triol.

Three esterifiable hydroxyl groups are contained in 1,3,5(10)-estratriene-3,16(α),17(β)-triol and 1,3,5-estratriene-3(β),16(α),17(α)-triol. The esters of this invention embraces all types, namely one with only one of these hydroxyl groups esterified, one with two of them esterified, and one with all three of them esterified.

The esters of this invention can be produced by the known process of esterification of the hydroxyl groups.

For instance:

(1) 1,3,5-estratriene-3,16(α),17(β)-triol or 1,3,5(10)-estratriene-3(β),16(α),17(α)-triol is made directly to react with a desired acid.

(2) 1,3,5(10)-estratriene-3,16(α),17(β)-triol or 1,3,5-estratriene-3(β),16(α),17(α)-triol is made to react in an organic solvent like pyridine, dichloroethane, benzene, cyclohexane with a desired acid anhydride.

(3) 1,3,5(10)-estratriene-3,16(α),17(β)-triol or 1,3,5-estratriene-3(β),16(α),17(α)-triol is dissolved in an aqueous solution of an alkali metal hydroxide like caustic soda or caustic potash and made to react with a desired acid halogenide like chloride, bromide, or iodide.

By these processes, a desired ester can be obtained. The acids employed in the above-mentioned processes of ester production are monobasic saturated fatty acid with 2 to 6 carbon atoms and benzoic acid; as such fatty acid may be taken acetic acid, propionic acid, butyric acid, valeric acid and caproic acid.

As actual examples of esters embraced by this invention may be mentioned the following:

- (i) 1,3,5(10)-estratriene-3,16(α),17(β)-triol triacetate, M.P. 126-127° C.;
(ii) 1,3,5(10)-estratriene-3(β),16(α),17(α)-triol triacetate, M.P. 162-164° C.;
(iii) 1,3,5(10)-estratriene-3,16(α),17(β)-triol 16,17-diacetate, M.P. 193-195° C.;
(iv) 1,3,5(10)-estratriene-3,16(α),17(β)-triol tripropionate, M.P. 99-101° C.;
(v) 1,3,5(10)-estratriene-3,16(α),17(β)-triol 16,17-dipropionate, M.P. 127-130° C.;
(vi) 1,3,5(10)-estratriene-3,16(α),17(β)-triol 16-monopropionate, M.P. 205-207° C.;
(vii) 1,3,5(10)-estratriene-3,16(α),17(β)-triol tributyrate oil;
(viii) 1,3,5(10)-estratriene-3,16(α),17(β)-triol tri-valerate oil;
(ix) 1,3,5(10)-estratriene-3,16(α),17(β)-triol tri-caproate oil;

- (x) 1,3,5(10)-estratriene-3,16(α),17(β)-triol tribenzoate, M.P. 168-169° C.;
 (xi) 1,3,5(10)-estratriene-3,16(α),17(β)-triol 3-monobenzoate, M.P. 227-228° C.;
 (xii) 1,3,5(10)-estratriene-3,16(α),17(β)-triol 3-acetyl 16,17-dipropionate, M.P. 77-78° C.

Comparison of the duration of estrogenic action by vaginal smear test between the esters of this invention and 1,3,5(10)-estratriene-3,16(α),17(β)-triol is made in Table I.

In this test, the test solutions were made by dissolving the esters of this invention in a mixture of sesame oil 70% and benzyl benzoate 30%, while the control was a solution of 1,3,5(10)-estratriene-3,16(α),17(β)-triol in propylene glycol.

For testing, these test solutions and the control were respectively injected into groups of more than 10 ovariectomized mice and the number of days on which more than 60% of these mice exhibited estrus was compared. The quantity of each ester was expressed in terms of estriol equivalent.

TABLE I

Comparison of the duration of estrogenic action on vaginal smear test

Compounds	Dose (μg.)	Duration (Day)
1,3,5(10)-estratriene-3,16(α),17(β)-triol (control)	2,000	15
	200	4
	20	0
1,3,5(10)-estratriene-3,16(α),17(β)-triol triacetate	30	8
	5	5
1,3,5(10)-estratriene-3,16(α),17(β)-triol triacetate	30	5
	5	3
1,3,5(10)-estratriene-3,16(α),17(β)-triol 16,17-diacetate	30	2
	5	0
1,3,5(10)-estratriene-3,16(α),17(β)-triol 16,17-dipropionate	30	3
	30	16
1,3,5(10)-estratriene-3,16(α),17(β)-triol tripropionate	5	11
1,3,5(10)-estratriene-3,16(α),17(β)-triol tributylate	30	22
1,3,5(10)-estratriene-3,16(α),17(β)-triol trivalerate	5	2
1,3,5(10)-estratriene-3,16(α),17(β)-triol tricaproate	30	0
1,3,5(10)-estratriene-3,16(α),17(β)-triol tribenzoate	30	4
1,3,5(10)-estratriene-3,16(α),17(β)-triol 3-monobenzoate	30	0
1,3,5(10)-estratriene-3,16(α),17(β)-triol 3-acetyl 16,17-dipropionate	30	2
1,3,5(10)-estratriene-3,16(α),17(β)-triol 16-monopropionate	5	6
	30	10
	30	1

These results show that 1,3,5(10)-estratriene-3,16(α),17(β)-triol as esterified by monobasic saturated fatty acid with 2 to 6 carbon atoms or benzoic acid will have the duration of its estrogenic action prolonged; particularly the above-mentioned estriol triesters of acetic acid, propionic acid or butyric acid will have the duration remarkably extended and the said action considerably intensified, which is testified by Table II.

TABLE II

Comparison of estrogenic activities on uterine weight methods

Samples	Days after injection of samples			
	4	8	12	16
Uterine weight (mg.)				
Oil only (control)	12.2	13.3	11.0	14.9
1,3,5(10)-estratriene-3,16(α),17(β)-triol (control)	14.3	12.1	11.2	13.1
1,3,5(10)-estratriene-3,16(α),17(β)-triol triacetate	54.5	21.1	17.8	14.5
1,3,5(10)-estratriene-3,16(α),17(β)-triol tripropionate	88.5	77.1	52.2	29.1
1,3,5(10)-estratriene-3,16(α),17(β)-triol tributylate	45.6	52.7	41.6	24.1

Meanwhile, it has also been observed that 1,3,5(10)-estratriene-3,16(α),17(β)-triol with admittedly very weak estrogenic effect can have its effect and duration markedly enhanced through esterification over those of 1,3,5(10)-estratriene-3,16(α),17(β)-triol.

Thus, it has been made clear through the test of vaginal smear and uterine weight of ovariectomized mice that the effect and its duration of estriol can be increased through esterification. Next, the clinical effect will be explained.

When 10 mg. of estratriene-3,16(α),17(β)-triol tripropionate was administered in one dose to an ovariectomized woman, excretion of estriol in her urine lasted about 7 to 12 days, the maximum amount being excreted on the third day after injection. The vaginal epithelium proliferation, as measured in terms of smear index in vaginal smear test, continued for about 14 days, the maximum value being found between the 4th and the 8th day.

On the other hand, it was observed that only a single injection of 10 mg. of estriol tripropionate 5 to 7 days before full-term could remarkably shorten the stadium of labour.

The above-mentioned reaction and a striking clinical usefulness will never be expected from only a single administration of estriol; this was presumably due to the enhanced effect and its duration of esterified estriol. Shortening the stadium of labour and facilitating delivery, predicted by Puck et al. from many experimental and clinical observations, was for the first time practically and economically actualized by using esters of the present invention; this was also due to the enhanced softening and relaxing effect of cervical canal, derived from the improved elevation of efficacy and its duration.

Actual examples of ester production as covered by this invention are given in the following:

EXAMPLE 1

1,3,5(10)-estratriene-3,16(α),17(β)-triol tripropionate. Three grams of 1,3,5(10)-estratriene-3,16(α),17(β)-triol was dissolved in 60 cc. of pyridine; 30 cc. of propionic anhydride was added to the solution, which was then heated at 70° C. for 6 hours. The mixture was diluted with 100 cc. of ether, successively washed with n-HCl, 5%-Na₂CO₃ and water, and then dried over anhydrous sodium sulfate. Then, the ether was evaporated; and the residue was recrystallized several times from ethylalcohol, producing 3.5 g. of 1,3,5(10)-estratriene-3,16(α),17(β)-triol tripropionate with a melting point of 99 to 101° C.

EXAMPLE 2

1,3,5(10)-estratriene-3,16(α),17(β)-triol 16,17-diacetate. One gram of 1,3,5(10)-estratriene-3,16(α),17(β)-triol was added to 40 cc. of glacial acetic acid, was refluxed at 120 to 130° C. for three hours; the mixture was then poured into water. The separated crystals were filtered and recrystallized from ether, producing 1,3,5(10)-estratriene-3,16(α),17(β)-triol 16,17-diacetate with a melting point of 193 to 195° C.

EXAMPLE 3

1,3,5(10)-estratriene-3,16(α),17(β)-triol 3-monobenzoate. One gram of 1,3,5(10)-estratriene-3,16(α),17(β)-triol was dissolved in 600 cc. of n-NaOH and then 1 cc. of benzoyl chloride dissolved in 10 cc. of ether was dripped on the solution while being cooled by ice. The solution was then agitated for six hours at room temperature and left to stand overnight. The separated precipitate was filtered. The obtained substance, after being refined by alumina column chromatography, was recrystallized from methanol, producing 1,3,5(10)-estratriene-3,16(α),17(β)-triol 3-monobenzoate with a melting point of 227 to 228° C.

EXAMPLE 4

1,3,5(10)-estratriene-3(β),16(α),17(α)-triol triacetate. One gram of 1,3,5(10)-estratriene-3(β),16(α),17(α)-triol was dissolved in a mixture of 20 cc. of pyridine and 10

cc. of acetic anhydride, and then heated at 70° C. for six hours. The mixture was diluted with 50 cc. of ether, successively washed with n-HCl, 5%-Na₂CO₃ and water, and then dried over anhydrous sodium sulfate. Thereupon, the ether was evaporated and then the residue was recrystallized from ethyl alcohol, producing 1.1 g. of 1,3,5-estratriene-3(β),16(α),17(α)-triol triacetate with a melting point of 162 to 164° C. was obtained.

EXAMPLE 5

1,3,5(10)-estratriene-3,16(α),17(β)-triol 16-monopropionate. One gram of 1,3,5(10)-estratriene-3,16(α),17(β)-triol was dissolved in 10 cc. of propionic acid and heated at 110 to 120° C. for five hours. After cooling, the reactant was poured into water. The separated precipitate was filtered; the filter cake, after being refined by alumina column chromatography, was recrystallized from methanol, producing 1,3,5(10)-estratriene-3,16(α),17(β)-triol 16-monopropionate with a melting point 205 to 207° C.

EXAMPLE 6

1,3,5(10)-estratriene-3,16(α),17(β)-triol 3-acetyl 16,17-dipropionate.

One gram of 1,3,5(10)-estratriene-3,16(α),17(β)-triol was dissolved in 10 cc. of propionic acid and heated at 150° C. for five hours. After cooling, the reactant was thrown into water. The separated precipitate was filtered and recrystallized from ether, producing 1,3,5(10)-estratriene-3,16(α),17(β)-triol 16,17-dipropionate with a melting point of 127 to 130° C. This crystal was dissolved in a mixture of 15 cc. of dry pyridine, and 0.9 g. of acetic anhydride, and then left to stand at room temperature for 24 hours. The reaction mixture was mixed with 1 cc. of methanol, left to stand for two hours, then evaporated it to a syrup under reduced pressure. The syrup was dissolved in 50 cc. of ether, successively washed with n-HCl, 5%-Na₂CO₃ and further with water; then dried by addition of anhydrous sodium sulfate. By evaporating the solvent and recrystallizing from methanol, 1,3,5(10)-estratriene-3,16(α),17(β)-triol 3-acetyl 16,17-dipropionate with a melting point of 77 to 78° C. was obtained.

When the esters of this invention are to be used for treatment of vaginitis, cervicitis, menorrhagia, climacteric disturbance, etc. and for relief of difficulty in delivery, they can be prepared in appropriate forms, for instance; solution for injection, tablets for oral administration and tablets for vaginal use.

The said esters of this invention are soluble in the commonly-used solvents for injection, such as camelia oil and other vegetable oils or methyl oleate, methyl lactate, etc. Therefore, when these esters are adopted for injection, it is preferred to use the above-mentioned mediums.

Meanwhile, these esters may be prepared in the form

of tablets for oral administration using lactose, precipitated calcium carbonate, starch, etc. as dilution mediums. These esters may also be locally applied as vaginal tablets, in which case the dilution medium will preferably

5 be one that can disperse the tablet soon after it is inserted in the vagina; for instance (1) one that can chemically form by reaction with the water content of mucus in the vagina and disperse the tablet in a comparatively short time; (2) water-soluble solids, like polyethylene glycol;

10 (3) oils and fats that can swiftly melt at body temperature; (4) one that is not soluble in water but can absorb water, thereby swelling and dispersing in the vagina.

Process of preparation for clinical application is illustrated in the following:

15 (1) Injection in oil for parenteral use: One gram of 1,3,5(10)-estratriene-3,16(α),17(β)-triol tripropionate is dissolved in 100 ml. of camelia oil. After filtration the solution is filled into 1 ml. ampouls being sealed and sterilized at 120° C. for one hour.

20 (2) Tablets for oral administration: Ten grams of 1,3,5(10)-estratriene-3,16(α),17(β)-triol triacetate is mixed with well-dried lactose 80 g. and starch 7 g.

Using a paste prepared from 3 g. of starch and water as the binder, the granules of this mixture are prepared and 25 by the common method into tablets each 0.1 g. in weight.

(3) Tablets for vaginal use: Five grams of 1,3,5(10)-estratriene-3,16(α),17(β)-triol tripropionate, 57.6 g. of tartaric acid, 155 g. of lactose, and 14.7 g. of starch are mixed well and made into granules by the common method. These granules are dried overnight at 60° C. and then mixed evenly with 61.7 g. of sodium bicarbonate. The obtained substance is pressed into tablets each 0.3 g. in weight.

What is claimed is:

35 1. A pharmaceutical composition applicable in the treatment of vaginitis, cervicitis, menorrhagia, climacteric disturbance, and for induction of labour and shortening of labour stadium, comprising 1,3,5(10)-estratriene-3,16(α),17(β)-triol tripropionate and pharmaceutical dilution mediums, the components of said compositions being in pharmaceutically acceptable amounts.

40 2. 1,3,5(10)-estratriene-3,16(α),17(β)-triol tripropionate.
